UNITED STATES PATENT OFFICE.

ODIN SUNDLY, OF DEER PARK, WISCONSIN.

LOCK.

1,209,069.

Specification of Letters Patent. Patented Dec. 19, 1916.

Application filed October 5, 1914. Serial No. 865,167.

To all whom it may concern:

Be it known that I, ODIN SUNDLY, a citizen of the United States, residing at Deer Park, in the county of St. Croix, State of Wisconsin, have invented certain new and useful Improvements in Locks; and I do hereby declare the following to be a full, clear, and exact description of the invention, such as will enable others skilled in the art 10 to which it appertains to make and use the same.

This invention relates to a lock.

An object of the invention is to provide a lock which will be durable and efficient in 15 use and in which provision is made for the alteration of the parts in such manner that they may be changed to be operated by a number of different keys.

A further object of the invention is to so 20 construct the device that the locking means will be automatically operated when inserted in the body of the lock.

With these and other objects in view, such as will appear as the description progresses, 25 my invention comprises the combination and arrangement of parts as set forth in and falling within the scope of the appended claim.

Referring to the drawing: Figure 1 is a 30 perspective view of the device. Fig. 2 is a longitudinal sectional view. Fig. 3 is a section on line 3—3 of Fig. 2. Fig. 4 is a detail of the locking core detached.

Referring to the drawing wherein like 35 parts are indicated by like characters throughout the several views:—My device comprises a body portion 1 made of suitable metal and having a longitudinally extending hole 2 therethrough which terminates at 40 the upper end in an elongated slot 3, the said slot being normally covered by means of a hinged plate 4.

On one side of the body portion 1 is 45 formed a pair of outwardly extending ears 5 between which is pivoted an arcuate shackle 6 on a bolt 7. In the end of this shackle 6 is formed a circular hole 8. The end of this shackle passes through an elongated slot 9 in one face of the member 1 and 50 the hole 8 is brought into registration with the hole in the body portion 1. However, the diameter of this hole 8 is less than the diameter of the hole 2 for a purpose to be hereinafter described. In order that this shackle 55 6 may be locked in the body portion 1, I have provided a plunger 10 which has a barrel

portion 11 on one end thereof, the diameter being equal to the diameter of the hole 2. Adjacent this barrel 11 is a reduced portion 12, the diameter of which is equal to the 60 diameter of the hole 8 in the shackle 6 and extending from this portion 12 is a circular shank 13 having a head 14 on the end thereof, the diameter of the said head being less than the diameter of the hole 8. Secured 65 to the shank 13 adjacent the head 14 is a pair of diverging leaf springs 15 which terminate adjacent the end of the portion 12.

Secured to the barrel 11 is an outwardly extending projection 16 which coöperates 70 with a notch 17 in one side of the body portion to determine the locking position of the bolt 10.

In operation the free end of the shackle 6 is placed in the slot 9 after having been 75 passed about the member which is to be locked and the head 14 of the bolt 10 is passed through the end of the hole 2 and through the hole 8 in the shackle 6, the bolt 10 is then pushed inwardly and the springs 80 15 are pressed against the shank 13 by the free end of the shackle 6, the barrel 11 is then rotated until the projection 16 registers with the notch 17 at which time further movement of the bolt inwardly causes the 85 ends of the springs 15 to pass beyond the free end of the shackle 6, at which time the ends of the springs fly outwardly and bear against the inner face of the said shackle so that when in this position the said bolt 90 10 may not be removed without pushing the free ends of the springs inwardly toward the shank 13 and thus the shackle will be held in its locked position.

The head 14 is provided with a plurality 95 of notches 18 which are adapted to coöperate with projections on the key to allow the latter to be moved over the shank 13 in a manner now to be described.

When it is desired to release the free end 100 of the shackle 6 a suitable key having a hole therein of a similar configuration to the head 14 is placed through the slot 3 and over the said head, the key is then pushed downwardly and the springs 15 are moved 105 inwardly toward the shank 13 at which time the bolt 10 may be withdrawn from the holes 2 and 8 and thus the free end of the shackle may be released. By changing the configuration of the head 14, the key used 110 may be changed and this may be done very readily when the bolt is removed or in order

that the key may be changed the end of the body portion 1 may be provided with a plurality of notches so that the projections 16 may be engaged in different notches as the 5 occasion arises.

It may be thus seen that I have provided a lock which is very simple in construction but yet efficient in use and I have so constructed the lock that the shackle thereof 10 will be automatically locked in closed position by resilient means, and I have so constructed the device that it may be very readily altered so as to necessitate the using of different keys.

15 While I have illustrated and described a particular embodiment of my invention, I have merely done so for the sake of convenience and I do not wish to be limited to that particular embodiment as it is obvious 20 that numerous changes may be made in the details of construction thereof without in any way departing from the spirit of the invention or exceeding the scope of the appended claim.

25 What is claimed is:—

In a device of the class described, a casing having a longitudinally extending hole

therethrough, a shackle pivotally secured to one face of said casing, the said casing having a slot in the said face through which 30 the free end of the shackle passes, said free end of the shackle having a hole therein registering with the hole in the body portion but of lesser diameter, a bolt arranged to be inserted in the hole in the body portion and having a reduced portion on one end thereof adapted to fit the hole in the end of the shackle, said reduced portion carrying a further reduced portion forming a shank, a head on the end of said shank, a 35 plurality of leaf springs secured to said bolt and arranged to lie beneath said head with their ends housed behind said reduced portion in unlocking position, a projection on the said bolt, and a notch in the said casing 40 arranged to coöperate with said projection to determine the locking position of the said bolt.

In testimony whereof, I affix my signature, in the presence of two witnesses.

ODIN SUNDLY.
